UNITED STATES PATENT OFFICE.

PETER DE MATTIA, OF PASSAIC, NEW JERSEY, ASSIGNOR TO DE MATTIA BROTHERS, INC., OF GARFIELD, NEW JERSEY, A CORPORATION OF NEW JERSEY.

TIRE-VULCANIZING MOLD.

Application filed September 8, 1926. Serial No. 134,279.

The present invention relates to tire vulcanizing molds, and more particularly to so-called "steam jacketed" molds in which the mold members are provided with steam chambers into which steam is admitted for the purpose of applying the heat necessary to the vulcanization of the rubber embodied in the tire.

Such molds are usually composed of two annular members each of which is provided with steam chambers provided with not only means to admit steam thereto but also means to permit the escape of water resulting from condensation of the steam. It is desirable in some cases that these mold members be used in a vertical position, and it has been found in practice that where the steam chambers extend entirely about the mold members there is some difficulty in removing therefrom the water which gathers therein as the result of condensation of the steam, and that the water flowing downward will gather and back up at the bottom of the chambers in sufficient volume to interfere to a considerable degree with the proper operation of the molds.

The object of the present invention therefore is to provide molds of such construction as to prevent the gathering and backing up at the bottom of the chambers and whereby the water will be promptly drained off and ejected from the mold members.

To accomplish this result I have provided means whereby the steam chambers of the mold members are divided preferably at points approaching the lower part thereof when the molds are in a vertical position, thus forming the steam chambers into sections, producing what might be termed the main steam chambers and also auxiliary steam chambers, and by providing means for draining both of the chambers of water, all as will be hereinafter set forth.

The invention therefore may be said to consist of a vulcanizing mold, the members of which are provided with separate and independent main steam chambers and auxiliary steam chambers with means for independently draining each of said chambers.

The present invention is shown in the accompanying drawing in which

Fig. 1 shows in front elevation, partially broken away to show underlying construction, a molding machine provided with my improved molds.

Fig. 2 shows a vertical sectional view taken on the line 2—2 in Fig. 1, looking in the direction of the arrow in that figure.

Fig. 3 is a view somewhat enlarged as compared with the other views showing in section the auxiliary steam chambers and parts of the main steam chambers, together with the means for draining them and for admitting steam into the auxiliary steam chambers.

Fig. 4 is a sectional view taken on the line 4—4 in Fig. 1 looking in the direction of the arrow in that figure.

Similar reference characters will be employed throughout the specification and drawings to designate corresponding parts.

As shown in the drawing the device comprises two annular mold members 1 and 2. Each of these mold members is preferably made of a single casting circular or annular in form and provided with a complementary mating joint 3 at or near their outer peripheries and engaging bead rings 31 on their inner peripheries. Each mold member is provided upon its inner face with a tire molding or shaping surface 4, and as indicated in Fig. 1 are mounted for use in a vertical position, one of them being fixedly mounted and the other mounted to have movement toward and from the fixed member so as to open and close the mold. Some of the supporting and operating mechanism of the apparatus is shown in Fig. 1 but as such mechanism constitutes no part of the present invention it will not be necessary to describe the same herein.

The mold members 1 and 2 are of the so-called "steam jacketed" type in which steam chambers are formed between the inner and outer walls. As illustrated there are two substantially concentric circular steam chambers 5 and 6 in each of the mold members, one being located near the outer periphery and the other near the inner periphery of the mold members. These steam chambers 5 and 6 are divided by partitions 7 and 8 preferably located near the bottom of the mold thus dividing the chambers into an upper or main section running from one partition 7 about the upper part of the mold to the partition 8 on the opposite side, and relatively smaller sections between the portions. The two sections thus formed in each steam chamber may be defined as the main chambers, being the upper part, and

auxiliary chambers, being the relatively small segmental part at the lower part extending between the partitions 7 and 8.

By means of piping 9 steam is admitted to the steam chambers, there being independent steam inlets 9' as indicated in Fig. 1 for both the main steam chambers and the auxiliary steam chambers.

The water which gathers in the chambers 10 by condensation of the steam will flow downward about and within the main chambers to a point adjacent the partitions 7 and 8 at which point it will drain therefrom through the piping 10 and the couplings 11. The water which gathers in the auxiliary chambers will flow therefrom through the couplings 12, also connected to the piping 10.

It will be noted that the couplings 11 and 12 enter the steam chambers at the lowest points to which the condensed water may flow by gravity and thus will be effective in permitting all water to escape from the steam chambers, and that the partitions 7 and 8 will prevent the water from the main chambers entering the auxiliary chambers.

The mold members preferably are provided with an air chamber 13 intermediate the concentric steam chambers and open as by the openings 14 to admit air thereto.

Having described my invention, I claim:—

1. In a steam jacketed mold for vulcanizing rubber tires, a plurality of concentric, circular steam chambers, partitions dividing each of such chambers into independent sections and independent steam inlets and independent drainage outlets for each section.

2. In a steam jacketed tire vulcanizing mold two vertically disposed substantially circular mold members, a plurality of concentric, circular steam chambers in each mold member, partitions dividing each of such chambers into independent sections, such partitions located below a horizontal line passing diametrically through the mold members, independent steam inlets for each section and independent steam outlets for each section positioned at the lowermost points in each section.

PETER DE MATTIA.
